UNITED STATES PATENT OFFICE.

ALBERT W. REYNOLDS, JR., OF PRINCETON, WEST VIRGINIA.

DESIGN FOR AN ELECTRICAL-APPLIANCE PLUG.

Application filed May 4, 1926. Serial No. 17,567. Term of patent 14 years.

To all whom it may concern:

Be it known that I, ALBERT W. REYNOLDS, Junior, a citizen of the United States, residing at Princeton, in the county of Mercer and State of West Virginia, have invented a new, original, and ornamental Design for Electrical-Appliance Plugs, of which the following is a specification, reference being had to the accompanying drawings, forming a part thereof.

In these accompanying drawings:
Figure 1 is an elevation of an electrical appliance plug showing my new design, and
Figure 2 is a top plan view of the same.

I claim:

The ornamental design for an electrical appliance plug, as shown.

ALBERT W. REYNOLDS, JR.
